(57) **CLAIM**

I claim the ornamental design for a kid's microphone, as shown and described.

DESCRIPTION

FIG. 1 is a front perspective view of a kid's microphone showing my new design.

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown are included for the purpose of illustrating the portions of the kid's microphone that form no part of the claimed design.

1 Claim, 4 Drawing Sheets(56)
